UNITED STATES PATENT OFFICE.

ROBERT G. WALLACE, OF BEN AVON, PENNSYLVANIA, ASSIGNOR TO NATIONAL FIRE PROOFING COMPANY, OF PITTSBURGH, PENNSYLVANIA, A CORPORATION OF PENNSYLVANIA.

WALL CONSTRUCTION.

Application filed October 14, 1924. Serial No. 743,539.

The present invention relates to wall constructions and particularly to wall constructions embodying alternate courses of main and stepped header tiles in combination with a facing of blocks, including courses of header blocks extending into the spaces between the smaller members of the header tiles and the lower faces of the main tiles.

In walls of this character as heretofore constructed, the main tiles have embodied but a single thickness of wall at their inner and outer vertical sides, so that in case of the spalling off of one of said walls of the main tiles by fire the whole wall structure would be liable to fall, and at any rate would be beyond repair and would have to be torn down. An important feature of the present invention is the provision in a wall construction of this type of main tiles embodying cellular inner and outer side walls, each cellular side wall being composed of two parallel vertical webs spaced apart by transverse connecting webs, and stepped header tiles having spaced vertical webs in vertical alignment with the vertical webs of the sides of the main tiles. With this construction, in case of fire the web next to the fire of each main tile and of each header tile may spall off without seriously endangering the stability of the wall structure because each main and header tile will still have remaining a single vertical web at the side thereof nearest the fire which will prevent the wall from falling. Furthermore, the wall can later be repaired by simply plastering over the single web.

This cellular construction of the inner and outer side walls of the main tiles provides wider beds for the mortar joints when the main tiles are laid with their cells extending vertically and the mortar can flow into the cells and become keyed to the main tiles. This also tends to make the wall structure more stable. By reason of the cellular construction of the inner and outer side walls of the main tiles, the horizontal mortar joints between the lower faces of the header tiles and the upper end faces of the main tiles can be made discontinuous, thereby rendering the wall structure practically moisture proof.

The invention is illustrated in the accompanying drawings, in which:

Figure 1 is a transverse vertical sectional

view of a wall structure embodying my invention, the facing blocks being shown in elevation and the main tiles being shown partly in elevation and partly in section and the main tiles being laid on end;

Figure 2 is a view similar to Figure 1, the main tiles, however, being laid on the side and all of the tiles being shown in section;

Figure 3 is a view similar to Figure 1, but showing the main tiles of smaller size and a slightly modified form of header tiles for cooperation therewith;

Figure 4 is a view looking at the inner face of a wall constructed as shown either in Figure 1 or Figure 3 before the inner coating of plaster is applied, and

Figure 5 is an isometric view of one of the main tiles.

A wall constructed in accordance with my invention consists of alternate courses of main tiles A, stepped header tiles B and in combination therewith a facing consisting of blocks C and D, the blocks D forming header courses which extend into the spaces between the lower faces of the main tiles and the smaller members of the header tiles.

Referring to Figure 5, each main tile comprises parallel inner and outer cellular side walls, each of said side walls embodying parallel vertical webs 2 and 3 spaced apart by transverse connecting webs 4. The cellular side walls of the tile are connected by transverse webs 5 and 6 adjacent the ends of the cellular walls and by any desired number of intermediate transverse webs 7. When a main tile is laid with its cells extending horizontally, as shown in Figure 2, the transverse webs 5, 6 and 7 extend horizontally. The cellular side walls extend a slight distance above the web 5 and said web may be provided with a rib 8 the upper surface of which lies in substantially the same horizontal plane as the projecting ends of the cellular side walls of the tile. Each main tile, in the larger sizes, may have a web 9 intermediate the cellular side walls and parallel therewith and intersecting the transverse webs 5, 6 and 7. The rib 8 lies directly over this web. The main and stepped tiles may be provided with grooves 10 in their outer faces so as to cause a better adherence of the plaster and mortar to the faces of the tiles. It will be seen that

each main tile, as viewed in Figure 5, is of uniform rectangular cross section throughout its height and has its top and bottom faces in planes at right angles to the side faces of the tile, the tile being in effect in the form of a right parallelepipedon. Furthermore, the spacing between the vertical webs 2 and 3 of each cellular side wall is relatively small as compared with the spacing between the cellular side walls themselves.

Each stepped tile comprises two members 11 and 12, the member 12 exceeding the member 11 in height and the tile being provided with a continuous bottom slab 13 common to the two members.

In the construction shown in Figure 1 the main tiles are laid with their cells extending vertically. It will be seen that each stepped tile has spaced vertical webs 14, 15, 16 and 17 which are in vertical alignment with the vertical webs 2 and 3 of the cellular inner and outer side walls of the main tiles. Each stepped tile also has a vertical web 18 in vertical alignment with the intermediate vertical web 9 of the subjacent main tile. Mortar joints 19 are provided between the lower face of each stepped tile and the upper ends of the cellular side walls of the subjacent main tile. A mortar joint 20 may also be provided between the lower face of each stepped tile and the upper end of the web 9 of each subjacent main tile. The mortar beds 19 and 20 are discontinuous so that they do not form a through mortar joint between the lower face of a stepped tile and the upper end of the subjacent main tile or tiles.

The blocks C are spaced from the adjacent faces of the main and header tiles and the intervening space is free of mortar. The blocks D of the header courses extend into the spaces between the smaller members 11 of the header tiles and the lower faces of the main tiles. These header blocks D, however, leave spaces 21 between their inner ends and the webs 18 of the header tiles which spaces are not filled with mortar. Mortar joints 22 are provided between the upper faces of the header blocks D and the lower faces of the main tiles. Mortar joints 23 and 24 are also provided between the upper faces of the larger members 12 of the header tiles and the lower faces of the main tiles. The mortar joints 22, 23 and 24 are discontinuous. It will be seen that the mortar at the joints 19, 22 and 23 flows into the cells between the vertical webs 2 and 3 of the main tiles and is thereby keyed to the main tiles. It will also be seen that the mortar at the joints 19, 20, 22 and 23 and at the joints 25 between the lower faces of the header blocks D and the upper faces of the smaller members 11 of the header tiles flows into the grooves 10 of the header tiles and is thus keyed thereto.

This keying of the mortar to the main and header tiles adds to the stability of the structure.

The construction shown in Figure 2 differs from that shown in Figure 1 mainly in that the main tiles are laid with their cells extending horizontally. In this construction mortar joints 26 are provided between the upper ends of the cellular side walls of the main tiles and the lower faces of the stepped tiles. Mortar joints 27 are also provided between the ribs 8 of the main tiles and the lower faces of the stepped tiles. The mortar joints 26 and 27 are discontinuous and since the horizontal webs 5 of the main tiles are slightly below the upper ends of the cellular side walls and the upper surfaces of the ribs 8, horizontal channels 28 are formed between the upper ends of the side walls and the ribs 8 for receiving any moisture which may pass the mortar joints 26. Mortar joints 29 are provided between the upper faces of the members 12 of the header tiles and the lower faces of the main tiles, and mortar joints 30 are provided between the upper faces of the header blocks D and the lower faces of the main tiles. The mortar joints 29 and 30, however, are discontinuous since the header blocks terminate short of the vertical webs 18 of the header tiles. It will be noted that when the main tiles are laid with their cells extending horizontally the vertical webs 14, 15, 16 and 17 of the header tiles are in vertical alignment with the vertical webs 2 and 3 of the main tiles the same as is the case when the main tiles are laid with their cells extending vertically.

The construction shown in Figure 3 differs from that shown in Figure 1 only in that the main tiles are of smaller dimensions horizontally and the header tiles B' are correspondingly modified in dimensions. However the vertical webs of the header tiles in this modified construction are in vertical alignment with the vertical webs 2 and 3 of the main tiles.

In laying a wall of this character it will be understood that the main and header tiles will be laid so as to break mortar joints as is illustrated in Figure 4.

While I have illustrated and described the preferred embodiment of my invention it will be understood that the invention is not limited to the exact details of construction shown, but that changes may be made therein within the scope of the appended claims without departing from the spirit of the invention.

I claim:

1. A composite wall comprising a brick facing on the outer face thereof, formed of a plurality of stretcher courses between spaced header courses, and a backing formed of alternate courses of hollow main and header tiles, the header tiles having recesses

into which the inner portions of the header bricks of the facing extend, there being a web in each tile in close proximity to and parallel with the outer wall of each tile, at 5 the inner face of the wall structure and sufficiently close to said outer walls of the tiles and the inner plane of the wall, that if the outer walls of some of the tiles spall off, the load bearing portions of the tiles from the 10 webs of the said spalled tiles to the faces of the tiles adjacent to the brick facing will be of sufficient strength to support the load for which the wall was designed.

2. A composite wall comprising a brick 15 facing on the outer face thereof, formed of a plurality of stretcher courses between spaced header courses, and a backing formed of alternate courses of hollow main and header tiles, the header tiles having recesses 20 into which the inner portions of the header bricks of the facing extend, the bricks of the stretcher courses being spaced from the backing tiles to form an air space between said bricks and the tiles between header courses, 25 there being a web in each tile in close proximity to and parallel with the outer wall of each tile, at the inner face of the wall structure and sufficiently close to said outer walls of the tiles and the inner plane of the wall, and a similar web adjacent to opposite walls of each tile that if the said walls of some of the tiles spall off, the load bearing portions of the tiles from the webs to webs of said spalled tiles will be of sufficient strength to support the load for 30 which the wall was designed.

ing portions of the tiles from the webs of said spalled tiles to the faces of the tiles adjacent to the brick facing will be of sufficient strength to support the load for which 35 the wall was designed.

3. A composite wall comprising a brick facing on the outer face thereof, formed of a plurality of stretcher courses between spaced header courses, and a backing formed 40 of alternate courses of hollow main and header tiles, the header tiles having recesses into which the inner portions of the header bricks of the facing extend, the bricks of the stretcher courses being spaced from the backing tiles to form an air space between said 45 bricks and the tiles between header courses, there being a web in each tile in close proximity to and parallel with the outer wall of each tile, at the inner face of the wall structure and sufficiently close to said outer walls of the tiles and the inner plane of the wall, and a similar web adjacent to opposite walls of each tile that if the said walls of some of the tiles spall off, the load bearing portions of the tiles from the webs to webs of said spalled tiles will be of sufficient strength to support the load for 50 which the wall was designed.

In testimony whereof I have hereunto set 55 my hand.

ROBERT G. WALLACE.
